LIFTER AND CARRIER

Ralph F. Fink, Excelsior, Minn., assignor to
Toralf Worum, St. Paul, Minn.

Application May 6, 1944, Serial No. 534,398

5 Claims. (Cl. 294—16)

This invention relates to article lifting and handling devices and the primary object is to provide a simple, practical and convenient device which may be used for lifting, carrying and handling such articles as boxes, bales, cartons and other generally rectangular or rectilinear heavy and bulky objects which are difficult to grip and lift by hand.

To this end the invention resides in the provision of spaced, hingedly connected arms having handles at inner, connected ends and the outer ends of which arms are joined by elongated gripping plates, all so arranged that manipulation of the handles will cause the arms to draw the gripping plates into tight clamping engagement with the opposite sides of an article which is to be lifted. Such gripping or clamping engagement of the plates with the article will be maintained so long as the handles are held and lifted and the article may thus be carried whenever necessary and then released by opening the device.

Another object of my invention is to provide means for adjusting the device to the size of the articles to be lifted. A further object is to provide means for limiting the clamping or gripping action when the articles being handled are of a fragile nature, liable to injury should the gripping plates bear too hard on the sides of the article.

Still a further object is to provide a lifter and carrier of this nature wherein the handles are offset and staggered in such manner as to facilitate balancing and manipulation of the load.

These and other more detailed and specific objects will be disclosed in the course of the following specification, reference being had to the accompanying drawing, in which—

Fig. 1 is a perspective of my lifter and carrier, showing the same in operative position upon a box or carton, the latter being indicated in dotted lines.

Fig. 2 is an enlarged fragmentary perspective view of one of the arms of my device, showing one means for effecting length or size adjustment of the device.

Fig. 3 is a fragmentary end view of another modification of my device, showing means for limiting the intensity of the gripping action.

Referring now more particularly and by reference characters to the drawing, A designates a lifting and carrying device constructed in accordance with my invention and adapted for use upon an article B such as a box, carton, bale or similar object having parallel sides.

The device A comprises two duplicate or separate pairs of arms, designated generally at 5 and 6 and each pair comprises two individual arms 7 and 8. These individual arms 7 and 8 of each pair are overlapped and pivotally or hingedly connected at inner ends by means of rivets or similar fasteners 9. The outer ends of the arms are turned angularly downwardly as indicated at 10 and are riveted or otherwise suitably and rigidly secured to gripping plates or members 11 and 12. The gripping plates 11 and 12 are elongated, flat rectangular shapes and may have their inner surfaces roughened or ridged as indicated at 13. The plates may also be arcuate or curved in cross section as indicated for the plate 11a in Fig. 3 where the resulting concaved inner surface 14 thus provided will facilitate gripping engagement with the article to be lifted. However made it will be noted that the gripping plates 11 and 12 serve to rigidly connect the pairs 5 and 6 of arms and hold them in spaced and parallel relation.

Attention is called to the fact that the arms 7 of each pair 5 and 6 are relatively shorter than are the other arms 8 of the pairs and the longer arms are diagonally opposed or are connected to opposite gripping plates 11 and 12. Thus the pivots 9 are offset in opposite directions from a medial plane passing between the gripping plates 11 and 12. The importance of this arrangement will presently be made clear.

At their inner ends the longer arms 8 are offset or turned upwardly as indicated at 15 and then extended in the form of handles 16. The handles may be rounded and roughened as shown and are extended in relatively opposite though parallel directions from the hinged ends of the arms.

In operation the gripping plates 11 and 12 may obviously be spread apart and arranged over opposite sides of the article B and then by lifting the handles 16 the arms will be angularly operated about their pivots 9 in such manner as to force the plates into tight clamping engagement with the article so that it may be lifted and carried from place to place as may be required. The relative off center relation of the pivots 9, caused by the difference in length of the arms 7 and 8 and the opposite or diagonal relationship of the arms as described, is of great advantage in distributing the weight of the article and in balancing it, since the tendency which the load might have to swing about the center, were the pivots 9 in line, is thus averted. The oppositely extending handles 16 further facilitate the bal-

ancing of the load as it is carried, as will be obvious.

It may be desirable, in order to adapt the device to the handling of articles of greatly varying widths, to provide for length adjustment of at least one arm of each pair 5 and 6. Thus, as seen in Fig. 2, I may make one arm, say that designated at 8^a, in two sections 17 and 18 overlapped and slidably related and one provided with a bolt 19 projecting through a slot 20 in the other. Obviously by tightening a wing nut 21 on the bolt 19 the arm sections may be secured in any relatively adjusted position lengthwise. To secure the arm sections 17 and 18 from relative swinging movement or angular displacement they may be provided with lugs 22 and 23 and with the lug on each section overlying the edge of the other, such movements will be prevented.

Under some circumstances, as when the article being handled is of a fragile nature, it may be desirable to limit the clamping effect of the gripping plates 11 and 12 upon the article. As shown in Fig. 3, this effect may be accomplished by pivoting a link 24 to the free end of each handle 16 and forming a loop 25 on the other end of the link to slidably embrace the arm 7. A pin 26 is placed in any one of a series of spaced openings 27 in arm 1 to limit the inward movement of the loop 25 as the arms 7 and 8 buckle or swing about their hinge connection 9. By properly locating the pin 26 it will be obvious that the angular movement of the arms 7 and 8, bringing the gripping plates together, may be limited to prevent crushing the sides of the article being handled.

It is understood that suitable modifications may be made in the structure as disclosed, provided such modifications come within the spirit and scope of the appended claims. Having now therefore fully illustrated and described my invention, what I claim to be new and desire to protect by Letters Patent is:

1. A lifting device comprising two parallel pairs of arms, the individual arms of each pair being

hingedly connected at inner ends, gripping means on the outer ends of the arms, and handles extending in opposite directions from one arm of each pair.

5 2. A lifting device comprising two parallel pairs of arms, the individual arms of each pair being hingedly connected at inner ends, gripping means on the outer ends of the arms, and a handle extending from one arm of each pair, said handles being turned in opposite directions with respect to each other and extending from diagonally opposed arms of the respective pairs.

10 3. A lifting device comprising two pairs of arms, the individual arms of each pair being hingedly connected at inner ends and the inner end of one arm of each pair being offset and extended in the form of a handle, gripping plates secured to and rigidly connecting the outer ends of the arms, and the said handles being formed on diagonally opposite arms of each pair and turned in relatively opposite and parallel relation with respect to each other.

15 4. A lifting device comprising two pairs of arms, one arm of each pair being longer than the other arm of that pair and the inner ends of the respective arms being hingedly connected, gripping plates rigidly connecting the outer ends of the corresponding arms of each pair, and the longer arm of one pair being connected to the same gripping plate as the shorter arm of the other pair.

20 5. A lifting device comprising two pairs of arms, one arm of each pair being longer than the other arm of that pair and the inner ends 35 of the respective arms being hingedly connected, gripping plates rigidly connecting the outer ends of the corresponding arms of each pair, the longer arm of one pair being connected to the same gripping plate as the shorter arm of the other pair, and handles extending from and connected to the inner ends of the longer arm of each pair of arms.
